UNITED STATES PATENT OFFICE

164,686

CLOCK OR SIMILAR ARTICLE

Isac Horowitz, New York, N. Y.

Application July 3, 1951, Serial No. 15,753

Term of patent 7 years

(Cl. D42—7)

To all whom it may concern:

Be it known that I, Isac Horowitz, a citizen of the United States, residing at New York city, in the county of New York and State of New York, have invented a new, original, and ornamental Design for a Clock or Similar Article, of which the following is a specification, reference being had to the accompanying drawing, forming part thereof.

In the drawing:

Fig. 1 is a front view of a clock showing my new design;

Fig. 2 is a side view of the clock;

Fig. 3 is a rear view of the clock; and

Fig. 4 is a face view of the pendulum weight, looking in the direction of the arrows in line 4—4 of Fig. 2.

The showing of a part of the clock in black is to indicate contrast of colors.

The essential features of my design for a clock are shown in full lines.

I claim:

The ornamental design for a clock or similar article, substantially as shown and described.

ISAC HOROWITZ.
